FIG. 1 is a front perspective view of a container showing the new design;
FIG. 2 is a rear perspective view of the container of FIG. 1;
FIG. 3 is a front elevational view of the container of FIG. 1;
FIG. 4 is a rear elevational view of the container of FIG. 1;
FIG. 5 is a left side elevational view of the container of FIG. 1;

FIG. 6 is a right side elevational view of the container of FIG. 1;
FIG. 7 is a top plan view of the container of FIG. 1; and,
FIG. 8 is a bottom plan view of the container of FIG. 1.
The broken lines immediately adjacent the solid contour lines along the left and right sides of the container represent the bounds of the claim. The remaining broken lines illustrate portions of the container. None of the broken lines forms part of the claimed design.

1 Claim, 7 Drawing Sheets
